BOBBIN THREAD CONTROLLED SIGNAL
FOR SEWING MACHINES

Ragnar W. Winberg, New York, N. Y.

Application August 24, 1943, Serial No. 499,759

6 Claims. (Cl. 112—218)

1

This invention relates to new and useful improvements in a bobbin thread controlled signal for sewing machines.

More specifically, the invention proposes the construction of an automatic signal attachment for sewing machines employing one or more needles and a like number of bobbins, one for each needle, and a stop signal for each of the bobbins in a manner to indicate that an approximate predetermined amount of thread still remains on the bobbin when the signal is given.

The object of having a predetermined amount of thread to be left is important for these reasons:

1. In some cases where the article is small or where the distance to be stitched is not too great the stitching can continue until it has reached the finishing point.

2. Another advantage of having a predetermined amount of cotton left on the bobbin is that the machine can be stopped in leisure or enough time to prevent the machine from continuing the stitching operation without the benefit of the bottom or bobbin thread.

3. Still another advantage is that the work will not have to be pulled back to be re-stitched because of the lack of thread on the bobbin. This eliminates waste time. Certain fabrics and materials cannot tolerate extra needle holes that the needle punched after having the work pulled back and restitched.

4. The operator will save time by not having to stop the machine to examine the amount of thread left on the bobbins so as to avoid stitching without thread on the bobbins.

The predetermined amount of thread to be left on the bobbin after the signal is given can be explained as follows: The amount of turns of thread that are wound on the top side of the bobbin that remain on the bobbin after the movable extendable member has been extended to close the signal circuit, can be used to finish stitching to a finishing point or to stop the machine in ample time to replace with another full bobbin to avoid continuance of the stitching operation without the bottom or bobbin thread.

Still further the invention proposes mounting a movable member slidably in the hollow cylindrical hub of a conventionally constructed bobbin and a stationary contact upon a portion of the sewing machine in a manner to close an alarm circuit when the movable member engages the fixed contact.

Another object of the invention proposes the provision of a resilient means tending to urge the movable member into an extended position from

2

the hub of the bobbin to engage the fixed contact and which may be retained in an inoperative position by the thread wound upon the hub of the bobbin so that when the thread is nearly consumed the movable member will be released, to be urged into its operative position by the resilient means.

Still another object of the invention proposes providing the movable member with a pair of adjacent resiliently mounted contact members which will successively be urged away from the fixed contact as the loop of thread passes around the bobbin during the sewing operation so that the one of the resiliently mounted contact members will make contact with the fixed contact at all times in a manner to cause the alarm circuit to be continuously closed.

It is a further object of this invention to construct a bobbin thread controlled signal attachment for a sewing machine which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure—

Fig. 1 is a side elevational view of a sewing machine having a bobbin thread controlled signal attachment constructed in accordance with this invention.

Fig. 2 is an enlarged horizontal sectional view taken on the line 2—2 of Fig. 1.

Fig. 3 is a fragmentary sectional view taken on the line 3—3 of Fig. 2.

Fig. 4 is a vertical sectional view of the bobbin per se.

Fig. 5 is a horizontal sectional view taken on the line 5—5 of Fig. 4.

Fig. 6 is a view similar to Fig. 4 but illustrating the position of the parts when thread is wound upon the bobbin.

Fig. 7 is a perspective view of the movable member used in this first form of the invention.

Fig. 8 is a schematic wiring diagram of the device.

Fig. 9 is an enlarged view similar to a portion of Fig. 3 but illustrating a modification of the invention.

Fig. 10 is a perspective view of the movable member used in the form of the invention shown in Fig. 9.

The signal attachment for sewing machine bobbins, according to this invention, is used in combination with a conventionally constructed sewing machine 10 having one or more reciprocating needles 11. On the drawing, the sewing machine 10 is shown having two needles, but this is merely by way of illustration. The machine 10 is further characterized by the fact that it has a bobbin case carrier 12, associated with a loop taker of any well known form, for each of the needles 11, and each of the bobbin carriers 12 contains a spool-like bobbin 13. The bobbin case may be provided with any suitable latching means for retaining the bobbin therein. The bobbin carriers 12 are located in the bottom portion of the sewing machine 10, and over each of which there is a sliding plate 14. Reference numerals 15 indicate the openings for the needles 11. The sewing machine functions in the usual manner in that the top loop of thread for forming the stitch normally passes around the bobbin carrier and bobbin during the sewing operation. Further details of the construction of the sewing machine 10 will not be given in this specification as they form no part of this invention.

The spool-like bobbin 13 is characterized by a hollow cylindrical hub 16 and end flanges 17 so that thread may be wound upon the hub between the end flanges. A movable member 18 is slidably mounted in one end of the hollow cylindrical hub 16 of the bobbin 13. This movable member 18 is of inverted cup-shape with its closed end forming a contact element 19 which normally projects from the face of its adjacent end flange 17. Oppositely disposed sides of the movable member 18 are formed with laterally extending projections 20. These projections 20 engage complementary slots 21 formed in the sides of the hub 16 of the bobbin for limiting movement of the movable member to the vertical and to prevent the movable member from becoming disengaged from the hub 16. The projections 20 serve a further useful purpose in holding the movable member in its retracted position shown in Fig. 6 as will become clear as this specification proceeds.

A stationary contact 22 is mounted upon the sewing machine 10, and more particularly upon the cover plate 14 above the longitudinal center of the hub 16 of the bobbin 13. A spring 23 is coaxially wound upon the hub 16 of the spool 13 and operates between the projected ends of the projections 20 and the adjacent end flange 17 of the bobbin 13 for urging the movable member 18 into an extended position from the end of the hub 16 in which its contact element 19 will contact the stationary contact 22 as indicated by dot and dash lines 19' in Figs. 3 and 8.

In Fig. 8 a schematic wiring diagram of an alarm circuit 24 is shown. Each of the bobbins 13 has a similar alarm circuit 24. Each circuit 24, includes in series a source of power, the bobbin 13, the fixed contact 22 and a visual alarm 25 comprising an electric lamp mounted upon a portion of the sewing machine 10. With this construction when the contact element 19 engages the fixed contact 22 the circuit will be completed and the electric lamp 25 will be illuminated.

The operation of this form of the invention is as follows:

Thread 26 is wound upon each of the bobbins 13 with the movable members 18 held in a depressed condition. The thread 26 is wound over

and against the lateral projections 20 of the movable members 18 for holding the movable members 18 retracted against the action of the springs 23. The bobbins 13 are then returned to their bobbin carriers 12 and the cover plates 14 are closed bringing the fixed contacts 22 into position over the movable members 18. The sewing machine is then operated in the usual manner and this continues until the thread 26 on one of the bobbins is used up to the point where it releases the movable member 18 to be urged outwards by its respective spring 23. The movable member 18 will then be extended causing the contact element 19 to engage the contact 22 closing the circuit 24 and illuminating its respective lamp 25. This will indicate to the operator of the machine that all of the thread on the bobbin 13 which controls that lamp has been nearly used. If the machine is not stopped immediately, for replenishing the supply of thread on the bobbin 13, the loops of thread formed by the reciprocating needle will continue to pass around the bobbin breaking the circuit causing the lamp 25 to flicker until the machine is stopped.

In the modification of the invention shown in Figs. 9 and 10, the construction of the signal attachment is similar to that previously described, except for the provision of means for preventing the lamp 25 from flickering if the machine is not stopped immediately after all the thread has been consumed on one of the bobbins 13.

This means comprises a pair of adjacent resiliently mounted contact elements 29 which project from the top of the movable member 18. Each of these contact elements 29 is mounted within an appropriate cavity formed in the movable member 18 and urged into an extended position by means of springs 30 also mounted within the cavities. These springs 30 possess merely enough tension to maintain the contact elements 29 in the extended positions illustrated in Fig. 9. With this construction, if the machine is not stopped immediately after the thread upon the bobbin has been used up, the loops of thread will pass around the bobbin 13 and successively pass between the contact elements 29 and the fixed contact 22 so that one contact element 29 will be always engaging the fixed contact 22 preventing the circuit from being broken by the passing thread.

Means is provided for holding one of the contact elements 29 in a retracted position against the action of its spring 30, permitting the circuit 24 to be broken if desired to have the lamp 25 flicker. This means comprises a lug 31 formed on one of the contact elements 29. This lug 31 engages a bayonet slot formed in the side of the movable member 18. The bayonet slot 32 has a long arm and an adjacent short arm. When the lug 31 is in position in the long arm, as shown in Figs. 9 and 10, the contact element 29 will be in an operative position. However, when the lug 31 is moved into the short arm of the bayonet slot 32 the contact element 29 will be in its inoperative retracted position within the movable member 18.

In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications

coming within the scope of the invention as defined in the appended claims.

Having thus described my invention, what I claim as new and desire to secure by United States Letters Patent is:

1. In a device of the class described, a spool like bobbin for insertion in the bobbin carrier of a sewing machine and having a hollow cylindrical hub and end flanges permitting threads to be wound on the hub, a movable extendable member slidably mounted in one end of said hollow cylindrical hub and having a contact element, a lateral projection from said extendable member passing through a slot in the side wall of said hub and over which said thread is to be wound for holding the extendable member retracted in said hub, resilient means operating between one end flange of said bobbin and said projection for urging said extendable member into an extended position in which said contact element will be extended from the face of the other of said flanges when the thread is nearly completely unwound from said hub, and a stationary contact mounted on said sewing machine at a point adjacent said bobbin to be engaged by said contact element when in extended position for completing a circuit to a signaling device.

2. In a device of the class described, a spool like bobbin for insertion in the bobbin carrier of a sewing machine and having a hollow cylindrical hub and end flanges permitting threads to be wound on the hub, a movable extendable member slidably mounted in one end of said hollow cylindrical hub and having a contact element, a lateral projection from said extendable member passing through a slot in the side wall of said hub and over which said thread is to be wound for holding the extendable member retracted in said hub, resilient means operating between one end flange of said bobbin and said projection for urging said extendable member into an extended position in which said contact element will be extended from the face of the other of said flanges when the thread is nearly completely unwound from said hub, and a stationary contact mounted on said sewing machine at a point adjacent said bobbin to be engaged by said contact element when in extended position for completing a circuit to a signaling device, said movable member being of inverted cup-shape and said contact element comprising the closed end thereof.

3. In a device of the class described, a spool like bobbin for insertion in the bobbin carrier of a sewing machine and having a hollow cylindrical hub and end flanges permitting threads to be wound on the hub, a movable extendable member slidably mounted in one end of said hollow cylindrical hub and having a contact element, a lateral projection from said extendable member passing through a slot in the side wall of said hub and over which said thread is to be wound for holding the extendable member retracted in said hub, resilient means operating between one end flange of said bobbin and said projection for urging said extendable member into an extended position in which said contact element will be extended from the face of the other of said flanges when the thread is nearly completely unwound from said hub, and a stationary contact mounted on said sewing machine at a point adjacent said bobbin to be engaged by said contact element when in extended position for completing a circuit to a signaling device, said resilient

means, comprising a spring coaxially wound upon said hub and operating between said lateral projection and adjacent end flange.

4. In a device of the class described, a spool like bobbin for insertion in the bobbin carrier of a sewing machine and having a hollow cylindrical hub and end flanges permitting the thread to be wound on the hub, a movable extendable member slidably mounted in one end of said hollow cylindrical hub and having a pair of adjacent resiliently mounted contact elements, a lateral projection from said extendable member passing through a slot in the side wall of said hub and over which said thread is to be wound for holding the extendable member retracted in said hub, resilient means operating between an end flange of said bobbin and said projection for urging said extendable member into an extended position in which said contact elements will be extended from the face of the other of said flanges when the thread is nearly completely unwound from said hub, and a stationary contact mounted on said sewing machine at a point adjacent said bobbin to be engaged by said elements when in extended position to complete a circuit to a signaling device.

5. In a device of the class described, a spool like bobbin for insertion in the bobbin carrier of a sewing machine and having a hollow cylindrical hub and end flanges permitting the thread to be wound on the hub, a movable extendable member slidably mounted in one end of said hollow cylindrical hub and having a pair of adjacent resiliently mounted contact elements, a lateral projection from said extendable member passing through a slot in the side wall of said hub and over which said thread is to be wound for holding the extendable member retracted in said hub, resilient means operating between an end flange of said bobbin and said projection for urging said extendable member into an extended position in which said contact elements will be extended from the face of the other of said flanges when the thread is nearly completely unwound from said hub, and a stationary contact mounted on said sewing machine at a point adjacent said bobbin to be engaged by said elements when in extended position for completing a circuit to a signaling device, and means for holding one of said contact elements retracted.

6. In a device of the class described, a spool like bobbin for insertion in the bobbin carrier of a sewing machine and having a hollow cylindrical hub and end flanges permitting the thread to be wound on the hub, a movable extendable member slidably mounted in one end of said hollow cylindrical hub and having a pair of adjacent resiliently mounted contact elements, a lateral projection from said extendable member passing through a slot in the side wall of said hub and over which said thread is to be wound for holding the extendable member retracted in said hub, resilient means operating between an end flange of said bobbin and said projection for urging said extendable member into an extended position in which said contact elements will be extended from the face of the other of said flanges when the thread is nearly completely unwound from said hub, and a stationary contact mounted on said sewing machine at a point adjacent said bobbin to be engaged by said elements when in extended position to close a circuit to a signaling device, and means for holding one of said contact elements retracted, comprising a lug projecting from one of said contact elements and

7
engaging a complementary bayonet slot formed
in said movable member.
